UNITED STATES PATENT OFFICE.

ANDREW LIVESEY, OF MANCHESTER, ENGLAND.

SPREADING ROLLER FOR WEB MATERIALS.

Application filed October 25, 1921. Serial No. 510,381.

To all whom it may concern:

Be it known that I, ANDREW LIVESEY, a subject of the King of Great Britain, residing at 3 and 5 Brierley Street, London Road, 5 Manchester, England, have invented new and useful Improvements in Spreading Rollers for Web Materials, of which the following is a specification.

My invention relates to rollers, bars, or 10 the like, for use in opening, scouring, or stretching, textile, or other, fabrics or materials, the said rollers, bars, or the like, being of the kind provided with a periphery, or active surface which is serrated or equivalently formed, or constructed, the object of 15 my invention being to provide an improved construction of such rollers, bars, or the like.

According to my invention a spring, or 20 springs, is, or are, coiled, or wound, or otherwise placed, round a roller, bar or the like, and between the coils, or convolutions, of the said spring, or springs, is, or are, coiled, or wound, a strip, or strips, of rubber, or other resilient, or equivalent, material. 25 The ends of the rubber strip or strips, are secured to the roller, bar, or the like, and the spring, or springs, is, or are, coiled, or wound, to any desired pitch so as to be in 30 tension, or at rest, when in place on the said roller, bar, or the like, and therefore to act by compression, or pitch, to hold and maintain convolutions of the rubber, or equivalent, strip, or strips, between the coils, 35 or convolutions, in place on the roller, bar, or the like.

In the accompanying drawing I have shown a broken side elevation of a bar in which my invention is embodied in one 40 form.

In the preferred construction here shown, two springs *a* and *a*² are employed one of which is coiled, or wound, right-handed, and the other coiled, or wound, left-handed, upon the body *c*, and between the coils, or convolutions, of each of these springs is, or are, placed a strip, or strips, of rubber, or other resilient material, of such cross-section as to give the necessary grip, or friction, upon the fabric, or material. Two such strips are shewn at *b* and *b*² in the accompanying drawing these being secured to the body *c* of the roller by means of the screws *d*.

What I claim is:

1. A bar for opening or stretching fabrics, or the like, comprising helices of resilient material wound upon the bar and secured at its opposite ends thereto, in combination with a helical spring, the convolutions of which alternate with the convolutions of the resilient material and serve to maintain the latter in place. 55

2. A bar for opening or stretching fabrics, or the like, comprising helices of resilient material wound in opposite directions and in series upon the bar and secured thereto, in combination with helical springs of opposite hand cooperating with the resilient helices, the convolutions of the springs alternating with the convolutions of the resilient material and serving to maintain the latter in position. 60 65 70

In testimony whereof I have signed my name to this specification in the presence of 75 two subscribing witnesses.

ANDREW LIVESEY.
